UNITED STATES PATENT OFFICE

FORREST A. KESSELER, OF HOUSTON, TEXAS, ASSIGNOR TO HOUSTON SPECIALTY CORPORATION, OF HOUSTON, TEXAS, A CORPORATION OF TEXAS

COMPOSITOR'S STICK

Application filed October 9, 1928. Serial No. 311,391.

This invention relates to new and useful improvements in a composing stick.

One object of the invention is to provide a device of the character described, specially designed for use by a compositor in setting type and comprising novel means for clamping and holding the set type in the stick.

Another object of the invention is to provide a stick of the character described having a novel type of clamp jaw for engaging and holding the line of type as set and having novel means for locking the clamp jaw against movement relative to the stick and for releasing the same.

With the above and other objects in view the invention has particular relation to certain novel features of construction, operation and arrangement of parts an example of which is given in this specification and illustrated in the accompanying drawings wherein:

Figure 1 shows a plan view of the stick.

Figure 2 shows an edge view.

Figure 3 shows a sectional view taken on the line 3—3 of Figure 1.

Figure 4 shows a sectional view taken on the line 4—4 of Figure 3 and showing the clamp jaw in released position.

Figure 5 shows a transverse sectional view taken on the line 5—5 of Figure 4.

Figure 6 shows a sectional view also taken on the line 4—4 of Figure 3 showing the clamp jaw in locked position, and

Figure 7 shows a perspective view of the clamp jaw.

Referring more particularly to the drawings, wherein like numerals of reference designate similar parts in each of the Figures, the numeral 1 designates the body of the stick which is preferably formed of a long flat metallic plate having the over turned marginal flanges 2 at one edge whose inner side has the transverse indentations 3 spaced a uniform distance apart.

At one end the stick has the transverse fixed abutment 4. There is a clamp jaw designated generally by the numeral 5. At one side this jaw has the oblong bearing groove 6 to receive a free edge of the stick and at its other side the clamp jaw

has the oblong groove 7 to receive the free edge of the overturned flange 2, said clamp jaw being thus slidably mounted on the stick. This clamp jaw is formed hollow, and it is provided with a straight face which confronts and is substantially parallel with the inner face of the fixed abutment 4. Within the clamp jaw 5 there is a channel shaped dog 9, U-shaped in cross section and having the side flanges 10, 10 which fit closely within the hollow clamp jaw 5. This dog works through an oblong slot 11 in the end of the jaw 5 which abuts the flange 2 and the dog is provided with the transverse detents 12 adapted to engage in opposing indentations 3. The ends of the dog 9 fit closely against the corresponding ends of the jaw 5 and the side flanges 10, at one end have the aligned slots 13, in which there is a bearing pin 14, whose ends are anchored to the respective walls of the jaw 5. A spring 15 is coiled around this pin with one end working against the adjacent end of the jaw 5 and with its other end engaged underneath a transverse pin 16 whose ends are secured to the respective side flanges 10. This spring normally operates to hold the detents 12 out of mesh with the indentations 3. The construction described permits the dog to move toward and from the flange 2, with its face, which confronts the flange 2 always substantially parallel with said flange.

There is a segment 17 rotatably mounted on a transverse pin 18. One end of this pin has an enlarged head 19 which is fitted into one wall of the jaw and the other end 20 of the pin is reduced and threaded into the opposite wall of said jaw. The margin of the segment 17 works through the slot 21 of the jaw 5 and is thus rendered accessible. The segment 17 has the cams 22, 22 one on each side which ride against the flanges 10, 10.

The jaw 5 may be adjusted to the desired place along the stick and the segment 17 then turned by the thumb of the operator to thus actuate said cams to cooperate with the flanges 10 and thus seat and lock the detents 12 in the indentations 3 so as to ac-

curately locate said jaw, and the jaw will bear, throughout its length against the flange 2 to hold the jaw against movement and the line of type set in the stick will thus be held securely in position. When it is desired to adjust the jaw 5, the segment 17 may be moved in the opposite direction to release the cams 22 from the flanges 10 and the spring 15 will then operate to move the dog 9 and release the detents from said indentations to permit the adjustment of said clamp jaw.

From an inspection of Figure 5 it may be observed that the head 19 and the reduced end 20 of the pin 18 are concentric but are eccentric with the respect to said pin so that the pin may be turned to adjust the cams 22 with respect to the flanges 10 of the dog 9 as may be found desirable.

20. The face of the stick is gauged as shown at 23, the gauge marks being opposite the respective indentations 3. The stick is gauged to indicate the length of line of type to be set. In the present instances the stick is shown as gauged for pica and half pica measures.

While I have shown what I now consider to be the preferred form of the invention, it is obvious that mechanical changes may be made therein, and equivalents substituted for the parts shown and I reserve the right to make such changes and substitutions as may be found desirable within the principle of the invention.

35. What I claim is:

1. A composing stick having a fixed abutment and an upturned flange, a jaw movable along said stick, a dog in said jaw having a face parallel with said flange said flange and face being provided, one with spaced indentations and the other with detents adapted to engage in said indentations, a segment mounted in said jaw and operatable against the dog to effect the engagement of the detents in said indentations, yieldable means operatable against the dog and effective to move said dog bodily away from said flange to release the detents from said indentations when said dog is released by said segment.

50. 2. A composing stick having a marginal flange and a fixed abutment, a clamp jaw having a slidable engagement with said stick, said jaw being characterized by the provision of a yieldably mounted dog therein engagable with said flange and a manually operatable cam through which the dog may be actuated into engagement with said flange yieldable means acting on one end of the dog normally tending to hold the dog out of such engagement said yieldable means and said end of the jaw being effective to maintain the dog constantly in parallel relation with said flange.

65. 3. A composing stick having a fixed abut-

ment and an overturned marginal flange, a clamp jaw engaged with said stick and movable therealong, a dog yieldingly mounted within said jaw, said dog having a face which confronts said flange and having side flanges, a rotatable segment in the jaw having cams which cooperate with the side flanges, said face and said overturned flange being provided with detents adapted to intermesh.

75. 4. A composing stick having a fixed abutment and an overturned marginal flange, a clamp jaw engaged with said stick and movable therealong, a dog yieldingly mounted within said jaw, said dog having a face which confronts said flange and having side flanges, a rotatable segment in the jaw having cams which cooperate with side flanges, said face and said overturned flange being provided with detents adapted to intermesh, 85 and yieldable means acting on the dog and normally holding the detents out of mesh.

5. A composing stick having a fixed abutment, a movable jaw mounted on the stick, said abutment and jaw having opposing substantially parallel faces, said jaw being characterized by the provision of a dog which is housed therein and which is arranged to work through the jaw face and co-operate with the face of said stick, the 95 co-operating parts of said dog and stick having intermeshing teeth, means normally tending to hold said teeth out of mesh and manually operable means through which the dog may be actuated to mesh said teeth and 100 lock the jaw against movement on the stick.

6. A composing stick having a fixed abutment and an over turned marginal flange provided with spaced indentations, a clamp jaw movable along the stick said jaw being 105 characterized by the provision of a bearing and a yieldably mounted dog housed therein and working through said bearing and having locating detents adapted to engage in said indentations, means for moving the dog 110 toward and from said flange, the face of said dog fronting said flange being disposed to bear against the flange throughout its length.

7. A composing stick having a fixed abutment and an over turned marginal flange, a clamp jaw movable along the stick, said jaw having a bearing and being characterized by the provision of a yieldably mounted dog having a bearing face which works 120 through said bearing and confronts said flange and means for manually moving the dog bodily to seat said face against the flange throughout the length of said face.

8. A composing stick having a fixed abutment and an over turned marginal flange provided with spaced indentations, a clamp jaw having a face confronting said flange and having a bearing, said jaw movable 125

along the stick said jaw being characterized by the provision of a dog having a detent, means for manually operating the dog through said bearing to engage the detent in its opposing indentation.

5 In testimony whereof I have signed my name to this specification.
